ABSTRACT OF THE DISCLOSURE

A signal amplifier switching system for substituting an amplifier into a multi-amplifier multi-channel recording/reproducing device upon indication of a defective amplifier is constructed with a signal amplifier in each channel, one of the signal amplifiers in one of the channels being employed for time signals. Each of the amplifiers has a detector coupled to the output thereof and responds to the absence of an auxiliary signal, which is continuously applied to all of the amplifiers, for switching the amplifier signal channel associated with the channel containing an absent auxiliary signal into the time signal amplifier channel. A detector coupled to the time signal amplifier similarly responds to a breakdown in the time signal amplifier for switching the time signal channel into one of the other signal channels.

The invention relates to a device for the simultaneous recording and/or reproduction of different signals in or from tracks of at least one record carrier. In such a device each signal is recorded through an associated amplifier in a track associated with said amplifier and one of said signals provides time information. A spare amplifier takes over the function of a signal amplifier immediately after the signal amplifier fails to operate.

Such devices are frequently used on airfields for recording the conversations between pilots and the ground station. In a known device there is provided a separate spare amplifier having its own track, which is always ready for use and which is switched on as soon as one of the other amplifier fails to operate.

According to the invention the time signal amplifier serves as a spare amplifier for the signals not providing time information, which amplifier continues operating as a time signal amplifier and/or one of the other amplifiers serves as a spare amplifier for the time signal, the latter amplifier continuing operating as an amplifier for its own signal.

This has the advantage that a separate spare amplifier may be dispensed with, while the full number of tracks can be employed for the useful signals.

In one embodiment of the device according to the invention means are provided for applying an auxiliary signal to the input of the amplifier, each of which amplifiers is associated with a switch which is controlled by the auxiliary signal detected at the output of the amplifier, said switch changing over the input of the relevant amplifier in the absence of the auxiliary signal to the input of the time signal amplifier and/or the time signal amplifier, in the absence of the auxiliary signal, to the input of any of the other amplifiers.

The advantage is that each amplifier is checked at all times as well as in the absence of an input signal.

In a further device embodying the invention the switch is formed by a photo-electric resistor arranged between the input of the relevant amplifier and the time signal amplifier, said photo-resistor being exposed, in the

absence of the auxiliary signal, to an incandescent lamp.

In this manner a simple and reliable change-over is obtained, and the disadvantage involved in mechanical contacts are avoided.

In a further device embodying the invention the time signal is attenuated when an amplifier is changed over. It is thus possible to overhear the time signal and the incoming signal selectively.

In a further embodiment of the device according to the invention there is provided a blocking circuit which prevents the switch from switching back to the relevant amplifier, when the auxiliary signal has been lacking and has re-appeared. Even a transient failure of an amplifier is thus signalled continuously.

A still further embodiment of the device according to the invention comprises a locking member which prevents the change-over of a second signal after the change-over of a signal to a further amplifier. In the event of a second failure of the apparatus the signal already changed over can thus not be disturbed by a second signal.

The foregoing will now be explained more fully with reference to the following figures.

FIGURE 1 shows the basic diagram of a device according to the invention and

FIG. 2 shows a circuit diagram of a device according to the invention.

As is shown in FIG. 1, the signals are applied via the input I_1 to I_n to the amplifiers V_1 to V_n , to which amplifiers there is applied, in addition, an auxiliary signal H_s . The output signal is fed to the recording heads K_1 to K_n and, moreover, to detection members D_1 to D_n . These detection members are constructed so that, when the auxiliary signal fails to appear at the output of one of the amplifiers, for example, the amplifier V_2 , the switch S_2 is changed over and the signal of the input I_2 is switched over to the input I_1 of the time signal amplifier V_1 . The same occurs in the absence of the output signals of the other amplifiers with the exception of that of the time signal amplifiers V_1 , in which the switch S_1 is changed over and the time signal is applied to the input I_2 of the amplifier V_2 . When an amplifier fails to operate, a signalling device (not shown) produces an alarm, so that the defective amplifier can be replaced as soon as possible by another.

FIG. 2 shows a circuit diagram of one embodiment of the device according to the invention. The signals are fed to the inputs I_1 to I_n and the channel connected to the input I_1 serves for time information. The signals are amplified in the amplifiers V_1 to V_n , associated with the inputs I_1 to I_n , an auxiliary signal H_s being, in addition, fed to the inputs of said amplifiers. The output signals are fed to the heads K_1 to K_n , which are connected each in series with a resistor R_{A_1} to R_{A_n} respectively, to which resistors are connected the associated detection members D_1 to D_n . The voltages across said resistors R_{A_1} to R_{A_n} are amplified and detected in the transistors TrA_1 to TrA_n . The potential of the base of the further transistors TrB_1 to TrB_n is chosen to exceed the potential of the emitters of said transistors to an extent such that these transistors do not convey current and the signalling lamps L_1 to L_n included in the collector circuits of said transistors do not burn. If one of the amplifiers V_1 to V_n , for example, V_2 , becomes defective, the signal at the base of the transistor TrA_2 will fail to appear so that this transistor is no longer conducting and the base of the transistor TrB_2 becomes more negative than the emitter thereof, said transistor thus becoming conducting and the lamp L_2 being ignited. Since the emitter of the transistor TrA_2 is fed via the resistor R_{B_2} , it becomes negative by the current passing through the transistor TrB_2 to an extent such that at a re-appearance of the signal the transistor TrB_2 is prevented from again conveying current, so that the lamp

L_2 continues burning. This lamp serves for signalling the defective amplifier V_2 . Voltage dividers formed by the resistors Rc_1 , Rd_1 , Re_1 to Rc_n , Rd_n , Re_n and the photo-resistors FwA_1 to FwA_n , which connect the collectors of the transistors TrB_1 to TrB_n to the positive supply voltage, has connected to it the bases of the transistors TrC_1 to TrC_n . The emitter circuits of said transistors include incandescent lamps A_1 to A_n respectively. In the unexposed state the value of the photo-resistors FwA_1 to FwA_n is so high with respect to the resistors Rc_1 , Rd_1 , Re_1 to Rc_n , Rd_n , Re_n that these bases are practically at the negative potential, so that these transistors are not conducting as long as the lamps L_1 to L_n do not burn. As soon as for example the lamp L_2 starts burning, the base of TrC_2 becomes more positive to an extent such that this transistor becomes conducting, so that the lamp A_2 is ignited and the photo-resistor FwA_2 is exposed, the resistance value thereof dropping to such a low level that said transistor continues conducting, even with the lamp L_2 extinguished. The lamp A_2 also illuminates the photo-resistor FwB_2 so that the input of the amplifier V_2 is connected through the low value of the photo-resistor FwB_2 to the input of the spare amplifier V_1 , while the signal of the input I_2 is recorded via the spare amplifier V_1 in the track associated herewith.

As soon as one of the amplifiers V_2 . . . V_n stops functioning, for example V_2 , and the transistor TrC_2 starts to conduct the bulb c connected in the common collector circuit lights up and throws its light upon the photo-resistor FwC . As a result the time-signal at the input S_1 is attenuated and fed to the amplifier V_1 . If, for example, the amplifier V_2 fails to operate and the transistor TrB_2 is conducting, the potential of its collector becomes more positive. Through the resistor Rf_2 and the diode Db_2 the base of the transistor TrD also becomes slightly more positive, while the base resistor Rg is chosen so high, that this transistor just remains non-conducting. As soon as a second amplifier, for example V_n , fails to operate, the current across Rg and also the potential of the base of TrD become so high that the latter becomes conducting, its collector becoming negative to an extent such that the diodes Dc_2 and Dc_n become conducting. This does not affect the state of TrC_2 , since the base potential thereof is positive, due to the low value of FwA_2 , to an extent such that this transistor remains conducting. The base of TrC_n , however, becomes negative to an extent such that this transistor cannot become conducting, since the resistance of the photo-resistor FwA_n is considerably higher because it is not exposed. Thus the change-over of the second defective amplifier is prevented. The diodes Dc_1 to Dc_n serve for preventing the more positive potential at the junction of the resistors Rc_2 and Rd_2 , when an amplifier, for example V_2 , fails to operate, from being transmitted to the junctions of the corresponding resistors Rc_1 and Rd_1 and so on of the other detection members D_1 and so on, since otherwise the transistors TrC_1 and so on might become conducting.

The cut-off of the transistors TrA_2 and so on can be eliminated by connecting, by means of the switch S , the base of TrD_2 via a diode Da_2 transiently to the positive supply voltage so that this transistor does not become conducting and the negative bias voltage of the emitter of TrA_2 is obviated and the initial state is restored.

The cut-off of the transistors TrC_2 and so on can be eliminated by transiently interrupting the current through the photo-resistor FwA_2 by means of the same switch. Since the lamp L_2 is extinguished, the resistor Re_2 is substantially at the full negative potential so that the transistor TrC_2 is cut off and the lamp A_2 ceases to burn.

When the time signal amplifier V_1 fails to operate, the photo-resistor FwB_1 is exposed to the lamp A_1 , so that the input I_1 is connected to the input I_2 of the amplifier V_2 . At the same time the lamp C illuminates the photo-resistor FwC so that the time signal is recorded in an attenuated state.

What is claimed is:

1. A signal amplifier switching system comprising a plurality of simultaneously operative signal input channels including at least one time signal channel, a plurality of signal amplifiers, each associated with one of said channels, means connecting each of said channels to its respective amplifier, first detecting means connected to the output of each of said amplifiers but said time signal channel amplifier and responsive to the absence of a signal from any one of said signal amplifiers but said time signal channel amplifiers for switching the signal channel input of said amplifier to the time signal channel, and second detecting means connected to the output of said time signal channel amplifier and responsive to the absence of a signal therefrom for switching the time signal channel input of said time signal channel amplifier to another of said signal input channels.

2. A signal amplifier switching system comprising a plurality of simultaneously operative signal input channels including at least one time signal channel, a plurality of signal amplifiers, each associated with one of said channels, means connecting each of said channels to its respective amplifier, means coupling an auxiliary signal to each of said amplifiers, first detecting means connected to the output of each of said amplifiers but said time signal channel amplifier and responsive to the absence of an auxiliary signal from any one of said signal amplifiers but said time signal channel amplifier for switching the signal channel input of said amplifier to the time signal channel, and second detecting means connected to the output of said time signal channel amplifier and responsive to the absence of a signal therefrom for switching the time signal channel input of said time signal channel amplifier to another of said signal input channels.

3. The combination of claim 2 wherein said detecting means includes switching means responsive to the detected absence of said auxiliary signal for accomplishing the said switching function, said switching means comprising a photo-electric resistor connected between the input of each signal channel amplifier but the time signal amplifier and the time signal amplifier, an incandescent lamp associated with each of said amplifier channels, said detecting means responsive to the absence of said auxiliary signal in one of said channels for igniting said lamp, and exposing each respective lamp associated with each respective channel to the associated one of said photo-electric resistors.

4. The combination of claim 2 further including means responsive to said switching of a signal channel into said time channel for attenuating said time signal.

5. The combination of claim 4 wherein said means for attenuating includes a photo-resistor connected in the input of said time signal channel amplifier and responsive to a further incandescent lamp in the detector means which is activated upon the switching of a signal channel into the input of the time signal channel, said time channel photo-resistor responding to said further lamp for attenuating said time signal.

6. The combination of claim 2 further including means for blocking said detecting means to prevent restoration of a signal amplifier upon re-appearance of the auxiliary signal associated therewith.
